UNITED STATES PATENT OFFICE.

THEODORE CORBETT, OF NEW YORK, N. Y.

PLATFORM SUPPORT FOR SUSPENDED SCAFFOLDS.

Application filed April 6, 1927. Serial No. 181,492.

This invention relates to platform supports and has for an object to provide an improved construction to be used especially for suspended scaffolds, whereby a more uniform support is presented.

Another object is to provide an improved support wherein the stringers are articulated in such a manner as to permit ready adjustment.

A still further object is to provide a platform support wherein the supporting members are pivotally secured together so that the strain will be transferred from one point to another in case of breakage of any of the suspending cables.

An additional object is to provide a support which may be easily dismantled but when in use, be capable of being supported by cables of any kind or by supporting machines now in common use.

In the accompanying drawing—

Figure 1 is a plan view of a platform support disclosing an embodiment of the invention.

25 Figure 2 is a longitudinal sectional view through Figure 1, on line 2—2.

Figure 3 is a sectional view through Figure 1 on line 3—3.

30 Figure 4 is a transverse sectional view through Figure 1 on line 4—4.

Referring to the accompanying drawings by numerals, 1 and 2 indicate side bars or stringers. Each of these stringers is made from two angle bars 3 and 4. Adjacent the 35 overlapping portion of bars 3 and 4, each bar is provided with a plurality of apertures 5 for receiving the various bolts 6, whereby the effective length of the stringers 1 and 2 may be varied by varying the amount 40 of overlap. A central supporting bar 7 is provided for each pair of side bars 1 and 2. The supporting bars 7 are telescopically fitted together in the same way as the stringers or side bars 1 and 2 and in addition, 45 are connected to the standard putlogs adjacent each end by suitable pins or bolts 8 and 9. The supporting bars 7 are preferably made from angle bars and are arranged with one flange extending downwardly so that the 50 platform boards 10 may rest on a comparatively broad and smooth surface. The stringers 1 and 2 are arranged with their flanges extending upwardly so as to present abutments against which the ends of boards 55 10 fit, as shown in Figure 1, whereby no

longitudinal movements of the boards can take place.

As indicated in Figure 3, the depending flange of the supporting bar 7 is cut away at each end so that the remaining part may fit flatwise against the upper surface of the putlogs 11 and 12 and so locate the upper surface of the bar 7 whereby it will be substantially in the same horizontal plane as the horizontal flanges of the stringers 1 and 2, thus giving a proper support at three points to the respective boards 10. Each of the stringers at each end has the horizontal flange bent downwardly to form lugs 13 and 14 for receiving suitable bolts for connecting the lugs to the putlogs 11 and 12. The bending downwardly of the horizontal flanges results in the vertical flanges extending beyond the horizontal flanges for presenting hinge members or apertured ears 15 and 16. The ear 15 of one stringer overlaps the ear 16 of the next adjacent stringer and suitable bolts 17 act as pintles for pivotally connecting the ears together. In this way, each set of stringers 1 and 2 and associated parts, form a section and the respective sections are pivotally connected together by the respective bolts 17. The resulting structure is a continuous platform support which may be easily raised and lowered in the usual way and may be easily set up or disassembled. By means of this structure, a continuous safety chain or support is supplied, running from one supporting machine to the other, whereby the failure of any one machine (cable and its hoist) would not be serious as its load would then be transferred to the adjacent machines. By making the stringers 1 and 2 extensible, any desired spacing of the machines is permitted.

The stringers 1 and 2 and associated parts, have been shown as metal, but if desired, they could be made of wood without departing from the invention. It will be noted that the boards 10 are short light boards and that they are placed on top of the stringers so as to run at right angles to the building to form the workman's platform or to form an overhead protecting shed. This effects a considerable economy in the amount of lumber used, as the boards 10 are not as thick as the planks heretofore used, and also, there is no overlapping. Where a safety or protecting shed is desired, suitable uprights are connected to the stringers 1 and 2 or

some other part of the respective sections, shaped in cross section with a bent down section of the horizontal flange of each stringer at each end, means for securing said bent down sections to said putlogs, and boards positioned on said stringers extending transversely of the stringers. ¹⁰

What I claim is:

- 5 The combination with a suspended scaffolding, having putlogs, of a platform support formed with a pair of stringers L-
